UNITED STATES PATENT OFFICE.

GEORGE W. McGILL, OF NEW YORK, N. Y.

DESIGN FOR INKSTANDS.

Specification forming part of Design No. **7,003**, dated November 25, 1873; application filed August 22, 1873.
[Term of Patent 7 years.]

To all whom it may concern:

Be it known that I, GEORGE W. McGILL, of New York city, in the county and State of New York, have invented a Design for an Inkstand, of which the following is a specification:

The nature of my design is fully represented in the accompanying drawing forming part of the specification, in which—

Figure 1 represents a top view of the stand without its cap. Fig. 2 represents a bottom view of the stand; and Fig. 3 represents a longitudinal view of the same with its cap.

A represents the top of the stand, B is the mouth, and C is the top of its ornamented base. D, Fig. 2, represents the ornamented annular groove in the bottom of the stand, ar-

ranged for the purpose of giving the stand an illuminated esthetic appearance from its top. E is the cap of the stand.

What I claim as my invention, and desire to secure by Letters Patent, is—

1. The design for an inkstand, having the dome-shaped top A and vertical ribbed base C, as herein shown and described.

2. The design for an inkstand, having the ornamental groove D, ornamental base C, and dome-shaped top A, as herein shown and described.

GEORGE W. McGILL.
